UNITED STATES PATENT OFFICE.

JAMES MILLS CAMPBELL, OF MILWAUKEE, WISCONSIN.

MEANS FOR DISTRIBUTING SOAP IN LIQUID OR PASTE FORM.

SPECIFICATION forming part of Letters Patent No. 761,759, dated June 7, 1904.

Application filed November 24, 1902. Serial No. 132,561. (No model.)

To all whom it may concern:

Be it known that I, JAMES MILLS CAMPBELL, residing at Milwaukee, in the county of Milwaukee and State of Wisconsin, have invented 5 a new and useful Improvement in Means for Distributing Soap in Liquid or Paste Form, of which the following is a description, reference being had to the accompanying drawings, which are a part of this specification.

10 My invention has relation to improvements in means for distributing soap in liquid or paste form.

The use of liquid soap for toilet purposes is very desirable and would no doubt be generally adopted if a suitable device for containing the liquid soap of such construction as to permit of the ready distribution or discharge of the soap in proper quantities to the users thereof were arranged in places where such 20 soap would naturally be used, such as in hotels, sleeping-cars, and other public places where large numbers of people are accommodated. The general adoption of liquid soap in places of the character referred to would 25 obviously not only prove to be most sanitary by reason of avoiding the necessity of different persons using the same soap, but likewise would prove to be a very economical expedient, as said liquid soap could be employed

30 exclusively as a substitute for soap in cake or powdered forms. Soap in the latter forms is not only equally expensive, but, furthermore, is consumed much more rapidly than would be the case with liquid soap (where there is no 35 waste) supplied in limited quantities to the user. Furthermore, soap in powdered form is objectionable, inasmuch as in order to maintain said soap in a dry state it is necessary to incorporate in the soap ingredients of a deleterious character.

40 The object of my invention is to provide a simple, cheap, and easily-operated device for the distribution in suitable quantity of soap in liquid or paste form.

45 With the above primary object in view the invention consists of the devices and parts or their equivalents, as hereinafter more fully set forth.

Referring to the drawings, Figure 1 is a

vertical sectional view of a device embodying 50 my invention, showing in full lines the upright position of the supporting-arms and in dotted lines the position of said arms when secured to a vertical wall-bracket or other device; and Fig. 2 is a plan view of the complete device.

The device consists of a receptacle 3, preferably divided into a receiving-compartment 4 and a discharging-compartment 5. The receptacle may be of any desirable material, 60 such as glass. The inner wall 6 of the receiving-compartment extends down about half-way to the bottom of the receptacle. The metal is then bent around and continued upwardly for a desired distance parallel with the wall 6 65 to form the inner wall 7 of the discharging-compartment. These two parallel walls 6 and 7, extending downwardly into the receptacle, form a beater or agitator for the liquid or paste soap, as it will be obvious that the contents whenever the receptacle is tilted or otherwise moved are disturbed or agitated by said walls, and hence the sediment is loosened and the pasty contents thereby prevented from thickening to such an extent as to prevent 70 free discharge out of the discharge-spout. The bottom of the receptacle is advisedly of rounded contour and merges on one side into the straight outer wall of the receiving-compartment and on the other side into the 80 straight outer wall of the discharging-compartment. The top of the discharging-compartment may be of rounded form, if desired. The upper end of the straight outer wall of the discharging-compartment has projecting 85 therefrom an outwardly-extending discharge-spout 8, which is preferably of outwardly-tapered form, so as to provide an opening 9 of diminished diameter.

While I prefer to form the inner walls 6 and 7, respectively, of the receiving and discharging chambers as shown in the drawings—viz., of two parallel and slightly-separated walls united at their lower ends by a rounded bend—yet I do not wish to be understood as restricting myself thereto, inasmuch as a single wall could be provided to form a separating-partition between the two chambers.

My invention contemplates employing, in connection with the receptacle for containing the liquid soap, said receptacle being preferably of the construction described, a means 5 for tiltably suspending said receptacle, so that a person desiring to use the soap is only required to tilt the device slightly in order to permit the liquid or paste soap to pass out of the discharge-opening into the hands of the 10 user. Referring to the particular mechanism shown for thus tiltably suspending the device, the numerals 10 10 indicate two supporting-arms, preferably curved in a direction away from the discharge-spout. One end of each 15 of these arms is provided with a broad foot or base 11, having openings through which bolts or equivalent securing devices may be passed and enter a suitable supporting medium. The opposite end of each arm is provided with a 20 pivot-eye 12 to receive the end of a transverse pivot-pin 13, said pin being rigidly secured between the inner walls 6 and 7 of the receiving and discharging compartments. The opposite ends of this pivot-pin work freely in 25 the pivot-eyes, and consequently the receptacle is capable of being readily tilted on the pivot for the purpose of discharging the contents of the receptacle. The receptacle is filled with the liquid soap advisably to the extent indicated in Fig. 1.

In Fig. 1 in full lines I show the ends of the arms 10, which are provided with the broad foot-pieces 11, as resting on a horizontal supporting medium 14 and bolted thereto. In 35 the same figure in dotted lines I show the same ends of the arms as secured to a perpendicular support 15, such as a wall or bracket. In either adjustment of the device the receptacle, of course, is tiltably suspended in a perpendicular position.

While I prefer to arrange the pivot-pin in the manner shown and described—that is to say, in the space between the inner walls 6 and 7 of the receiving and discharge compartments—yet I do not wish to be understood as limiting myself to that exact location, inasmuch as laterally-extending trunnions could project out from any desired opposite points of the receptacle.

50 I prefer to provide for the open upper end of the receiving-chamber a removable cover 16.

From the foregoing description it will be seen that I provide not only an exceedingly simple device for the purpose intended, but 55 also one which can be manufactured at a small cost and operated with a minimum of trouble by pressing gently on the discharge-spout 8.

What I claim as my invention is—

1. In a distributor for soap in liquid or paste 60 form, the combination with a receptacle having a receiving-compartment, said compartment provided with an opening for the introduction of the soap, and said receptacle also provided with a discharge-compartment separated from the receiving-compartment by a

wall having a lower opening whereby the two compartments are placed in open communication with each other, the said wall forming a beater or agitator for the contents of the receptacle, and said discharge-compartment provided with a projecting spout, of means for tiltably suspending the receptacle in an upright position.

2. In a distributor for soap in liquid or paste 70 form, the combination with a receptacle having a receiving-compartment, said compartment provided with an opening for the introduction of the soap, and said receptacle also provided with a discharge-compartment separated from the receiving-compartment by a downwardly-extending partition, the lower end of said partition terminating short of the bottom of the receptacle, whereby a communicating passage is formed between the two compartments, the said partition forming a 80 beater or agitator for the contents of the receptacle, and said discharge-compartment provided with a projecting discharge-spout, of means for tiltably suspending the receptacle in an upright position.

3. In a distributor for soap in liquid or paste 90 form, the combination with a receptacle having a receiving-compartment, said compartment provided with an opening for the introduction of the soap, and said receptacle also 95 provided with a discharge-compartment, the two compartments being separated by a partition, said partition terminating short of the bottom of the receptacle to form a communicating passage between the two compartments, and said partition formed by a downwardly-extending wall constituting the inner 100 wall of the receiving-compartment and an upwardly-extending wall bent upwardly from the lower end of the first-mentioned wall and 105 parallel therewith, and constituting the inner wall of the discharge-compartment, the said partition forming a beater or agitator for the contents of the receptacle, and said discharge-compartment provided with a projecting 110 spout, of means for tiltably suspending the receptacle in an upright position.

4. In a distributor for soap in liquid or paste 115 form, the combination with a receptacle having a receiving-compartment provided with an opening for the introduction of the soap, and said receptacle also provided with a discharge-compartment, the two compartments being separated by a partition, said partition terminating short of the bottom of the receptacle to form a communicating passage between the two compartments, and said partition formed by a downwardly-extending wall 120 constituting the inner wall of the receiving-compartment, and an upwardly-extending 125 wall bent upwardly from the lower end of the first-mentioned wall and parallel therewith and a short distance removed therefrom, and forming the inner wall of the discharge-compartment, the said partition forming a beater 130

or agitator for the receptacle, and said discharge-compartment provided with a projecting spout, a pivot-pin rigidly secured in the space between the inner walls of the receiving and discharging compartments and having its ends projecting laterally beyond the receptacle, and arms secured at their ends to a supporting medium, and having their oppo-

site ends pivotally secured to the projecting ends of the pivot-pin. ¹⁰

In testimony whereof I affix my signature in presence of two witnesses.

JAMES MILLS CAMPBELL.
